MICROPHONE SUPPORT

Byron F. Ryan, Los Angeles, Calif., assignor to
Warner Brothers Pictures, Inc., a corporation of
Delaware

Application October 3, 1938, Serial No. 232,989

4 Claims. (Cl. 248—358)

This invention relates to sound-wave detecting apparatus such as microphones and particularly to a mounting for such apparatus. This mounting has been designed for use on the end 5 of a boom used on motion picture sets wherein the microphone is suspended above, or proximate to, the source of sound and moved by the boom to follow the sound source.

In the use of a sensitive microphone on the end of a boom it becomes a problem to prevent extraneous sounds, caused by the movement of the microphone, from being detected and transmitted to the sound record. Generally, the boom arm is quite long and flexible, and vibrations 15 are sometimes introduced therein both vertically and horizontally, caused by movement of the boom or microphone at the end thereof.

The mounting is in the form of a mechanical filter which is adjustable so that it may be 20 tuned to eliminate certain frequencies, and is of a shape so as not to interfere with proper functioning of the microphone. The mount is a combination filter system which eliminates both high and low frequencies.

An object of the present invention, therefore, is to minimize the effects of moving a boom with a microphone suspended thereon during the sound pick-up operation.

Another object of the invention is to mount 30 a microphone so that it may be spatially adjusted without its being electrically affected.

A further object of the invention is to provide a mechanical filter mounting for eliminating mechanical vibrations of different frequencies 35 introduced by movement of the microphone.

A further object of the invention is to enable a mechanical filter mounting to be tuned for different loads.

Although the novel features which are believed to be characteristic of this invention are 40 pointed out with particularity in the claims appended herewith, the manner of its organization and the mode of its operation will be better understood by referring to the following description read in conjunction with the accompanying drawing forming a part thereof, in which

Figure 1 is a partial cross-sectional view of the microphone mounting as attached to a microphone boom;

Figure 2 is a cross-sectional view of the low frequency filter portion of the mounting taken along the line 2—2 of Fig. 1; and

Figure 3 is a plan view of the high frequency portion of the filter mounting taken along the 55 line 3—3 of Fig. 1.

Referring now to the drawing, in which the same numerals indicate identical elements, the end 5 of a microphone boom has connected thereto, by an adjustable coupling 6, a rod 7 having a flanged lower end 8. The element 5 may be the extendible end of the adjustable cross-arm of the boom shown in W. A. Mueller Patent 2,122,778 of July 5, 1938. Rotatably mounted on the rod 7 is a cap or cover 10 having a grooved or pulley portion 11, around which is a cable 13, one end of which is attached in an eye-bolt 15 on the portion 11. Fastened to the upper side of the pulley section by screws 16 is a cylindrical housing 18 to which is also fastened one end of a coil spring 19 at point 20. The other end of the coil spring 19 is attached to a collar 22 at 23, the collar 22 being pinned to the rod 7 by a pin 24. This arrangement permits the cover 10 to be rotated in one direction about the rod 7 when the cable 13 is pulled, and to be rotated in the other direction by the tension of spring 19 when the cable 13 is released. This mechanism permits the rotation of the microphone by the boom operator.

Attached to the cover 10 by screws 26 is a 25 conical-shaped shell 27 in which are elongated slots 28, the purpose of which will be explained hereinafter. Within the shell 27 is a fine-grained sponged rubber conforming to the shape of the shell and made up of two sections 30 and 31. Section 30 of the rubber has a hole therein to accommodate the shaft end 33 of a yoke member 32. The shaft 33 has a stud 40 threaded therein. In the upper end of the shaft 33 there are threaded three radially extending bronze 35 arms 34, 35 and 36 (see Fig. 2), in the slotted ends of which are inserted fin members 37, 38 and 39, respectively. That is, the arms 34, 35 and 36 are cylindrical with threaded ends to be inserted in tapped holes at the upper end of 40 the shaft 33. The fin members wedged into the slots at the other ends of the radial arms are of sheet bronze.

These elements are assembled by first placing the lower sponged rubber section 30 in position in the shell 27 with the cover 10 removed, then inserting the shaft end 33 up through the rubber, then threading the arms in position and then inserting the fins in the slots of the arms. The upper rubber section 31 is then placed in 50 the shell 27 and the cover 10 is then inserted and screws 26 are tightened. To obtain the desired frequency for the filtering action, the cover 10 is pressed onto the rubber to the proper degree; provision being made for tightening the 55

cover at any desired position by the elongated slots 28 in the shell 27. The lower sponged rubber portion 30 extends outside the lower rim of the shell, and the lower sides are cemented to the shell, as well as to the shaft 33. It has been found that by cementing these portions there is no tendency of the shaft 33 to leave the rubber or the rubber to leave the shell when the inertia of the microphone exerts a pressure 10 on the rubber during movement of the boom.

At the lower portion of the mount is found a yoke 42 which has a hole in the upper horizontal portion thereof to accommodate a stud 43 on the lower horizontal portion of the member 32. The yoke 42 is held on the stud by a nut 45 threaded on the stud 40. The lower ends of the yoke 42 are connected to an outer ring 46 of the high frequency filter portion of the mount and held thereto by wing nut-and-bolt combinations 47. An inner ring 50 is attached to the outer ring 46 by means of a flexible rubber band 51 interlaced between the two rings. Extending upwardly from the inner ring are bracket arms 53 terminating in a split collar 54 having a tightening screw 55. A spherical type microphone 57 having a curved baffle 58, as disclosed and claimed in copending application S. N. 223,237, filed August 5, 1938, is mounted on the bracket arms 53 by tightening the collar 54 about the connecting plug 59 of the microphone. An electrical cable 60 leads from the microphone to an amplifier, as is well known in the art.

From the above description it will be noted that there are two mechanical filters connected in series between the microphone 57 and the rod 7, the sponged rubber sections 30 and 31 and the weight of the elements suspended from shaft 33 eliminating the low frequency vibrations, and the stretched rubber bands 51 and the weight of the inner ring and microphone eliminating the high frequency vibrations. Thus, when the extendible end of the boom has a tendency to vibrate at a slow period, the upper filter will prevent the vibrations from affecting the microphone, while quick and sharp vibrations will be eliminated by the lower filter. Also, rotation of the microphone by cable 13 and spring 19 may set up certain vibrations which are damped out 50 and prevented from reaching the microphone with sufficient severity to be picked up thereby.

Another feature of the support is the conical shape of the lower portion of the upper filter which prevents reflections of sound waves and, consequently, reduces echo effects. This support has given improved results over other types of resilient mountings and even without the high frequency portions, has been found to be superior to the old types. Since this filter mounting may be tuned, it is suitable for microphones

of different weights within certain limits. That is, when the weight is varied as an element of the filter, the resiliency may also be varied to maintain the period of the filter at substantially the same value. 5

I claim as my invention:

1. A microphone support for minimizing vibration effects on said microphone set up by a flexible extension adapted to be moved for adjusting the position of said microphone comprising a conical-shaped shell having its larger diameter portion attached to one end of said extension and its smaller diameter portion in the direction of said microphone, a suspension shaft for supporting said microphone, a resilient material within and interposed between said shell and said suspension shaft and extending around said shaft externally of said shell, and a plurality of arms embedded in said resilient material and attached to said shaft. 10

2. A microphone support in accordance with claim 1 in which said arms extend radially from said microphone support and are connected to fin members extending into said resilient material. 20

3. A microphone support for minimizing vibration effects on said microphone set up by a flexible extension adapted to be moved for adjusting the position of said microphone comprising a conical-shaped shell having its larger diameter portion attached to one end of said extension and its smaller diameter portion in the direction of said microphone, a suspension shaft for supporting said microphone, a resilient material within and interposed between said shell and said suspension shaft and extending around said shaft externally of said shell, a plurality of arms embedded in said resilient material and attached to said shaft, and a closure for said shell for varying the pressure on said resilient material in said shell for changing the resonant period of said resilient material. 30 35

4. A mechanical filter for supporting a microphone suspended from a flexible support adapted to be moved for adjusting the position of said microphone comprising a conical-shaped shell connected to one end of said support, resilient material positioned in the lower conical portion of said shell, a shaft extending through said resilient material at the other end of said shell for supporting said microphone, a plurality of removable arms connected to the top portion of said shaft and extending over said resilient material, a second portion of resilient material mounted above said arms and within the upper portion of said shell, and means for covering said shell and exerting a pressure on said resilient material. 45 50 55
